TRANSFORMER WITH A CLOSED
MAGNETIC CIRCUIT

Pierre Souliary, Paris, France, assignor to l'Air
Liquide, Societe Anonyme pour l'Etude & l'Ex-
ploitation des Procedes Georges Claude, Paris,
France

Application October 15, 1936, Serial No. 105,769
In Germany October 25, 1935

3 Claims. (Cl. 171—119)

The present invention relates to transformers with a closed magnetic circuit and a controllable magnetic leakage obtained by stepless displacing of one of the windings with respect to a stationary winding. These transformers are used in the cases in which a reactive voltage drop is to be obtained, for instance in electric arc welding or in resistance welding.

In electric arc welding it is necessary that it should be possible to make the intensity of the welding current to assume all values between the limit values which it is desired to have available according to the nature of the metal and the bulk of the work to be welded, the diameter of the welding rods and the nature of their coating, etc. In the same way in resistance welding the transformers of this kind can be advantageously used as they permit the control of the welding current, particularly according to the thickness to the nature of the metal of the work.

In the transformers of this kind heretofore manufactured, the windings of the primary and secondary circuits are wound around a closed magnetic circuit, of rectangular or annular shape and their relative position is changed by displacing one of the windings with respect to the other, which is stationary. The rectangular construction requires a relatively large space in order to obtain all the desirable current ranges and the annular construction in practice has the same drawback. Further the latter presents certain difficulties in manufacture or requires the entirely curvilinear cutting of the sheets of the core, which increases the cost of manufacture and involves sheet wastes which are practically useless. The transformers designed according to the present invention avoid all these drawbacks and in particular occupy a small space and are easy to manufacture. The transformer is characterized in that its closed magnetic circuit is constituted on one hand by an incurvated part, along which the movable winding can be displaced, and, on the other hand, by one or more rectilinear parts, which bridges or bridge the ends of this incurvated part.

Preferably the incurvated part of the magnetic circuit is so shaped that it renders possible the displacement of the movable winding along an arc of a circle and for example along a half-circle and the rectilinear parts are constituted by two parallel cores and by a yoke perpendicular to these cores.

In order to obtain a predetermined range of controlled currents with the minimum expenditure of raw material it is advantageous to reduce

the number of turns of the movable winding and to connect in series with this movable winding a stationary winding having a number of turns which is equal to the number of the omitted turns of the movable winding. This stationary winding is magnetically coupled with the first stationary winding, the two stationary windings being for instance wound on the parallel opposite parts of the magnetic circuit.

The invention is illustrated by way of examples in the accompanying drawings in which:

Figure 1 is a transformer intended for use in electric arc welding,

Figure 2 is a modified form with an incurvated core of progressively varying section,

Figure 3 is a transformer in which one of the circuits includes a stationary winding and a movable winding, connected in series,

Figure 4 shows a device which allows the movable winding to assume elastic displacements, and

Figure 5 shows a transformer for electric arc welding and resistance welding.

In the Figure 1 the magnetic circuit consists of a semi-circular part 7 and of two cores 4 and 8; a yoke 9 closes this magnetic circuit. The winding which is stationary with respect to the magnetic circuit is shown at 1 and surrounds the core 4. It forms the secondary winding of the transformer and is connected to the electrode 3 and to the workpiece 3.

The second winding 5, which is therefore the primary winding, is connected to a network; it can rotate about an axis 6 and surrounds the semi-circular part 7 of the magnetic circuit. This axis can coincide, as in the case of the figure, with the centre of the semi-circular part of the magnetic circuit, or not. The winding 5 is so manufactured and disposed that, during its rotation, it can be displaced from a position of maximum coupling with the winding 1 to a position of minimum coupling. In Figure 1, the movable winding 5 is represented in full lines in its position of maximum coupling and in dotted lines in its position of minimum coupling. These two limit values of the coupling correspond to an angular displacement of 180° of the movable winding.

Owing to this arrangement of the magnetic circuit a very tight maximum coupling and a very loose minimum coupling are obtained and the space required is reduced.

The transverse sections of the magnetic circuit can be square or rectangular or present any shape ascertained as advantageous from the point of view of the utilization of the raw materials or of the ease of manufacture. The area of these

transverse sections can be constant everywhere, or vary in a continuous or discontinuous manner, particularly if it is of advantage to create zones of a more or less high saturation along the magnetic circuit, in order to obtain certain modes of distribution of the values of the secondary current in relation with the angular displacement of the movable winding.

In the Figure 2 the magnetic circuit consists of a parallellopedic yoke 16 and two cores 11 and 12, the transverse sections of which are unequal, the core 11 having the greater section. An curved piece 12 bridges the ends of these cores and its transverse section is progressively reduced from the transverse section of the core 11 to the transverse action of the core 13. The section of the core 11 is cross-shaped, which is advantageous in connection with the utilisation of the surface to be wound. The stationary winding is situated at 14, around the core 11, and the movable winding is shown at 18. Through the displacement of the movable winding in the direction of the arrow, the free space between the yoke 12 and the movable winding 16 progressively increases, which offers the advantage, as against a magnetic circuit with a constant section, that the current value changes less rapidly in the regions of tight coupling and therefore in the range of the higher current intensities, and changes more rapidly in the range of the lower current intensities.

In the Figure 3, relating to a transformer in which one of the circuits includes a stationary winding and a movable winding, connected in series, the magnetic circuit is constituted by a semi-circular yoke 16, two cores 17 and 18 and a rectilinear yoke 19. The primary is formed by two coils connected in series: the one 20 is stationary and wound around the core 17; the other 21 is movable and can rotate about the axis 22, which, in this illustrated construction, coincides with the axis of the semi-circular part of the magnetic circuit. The secondary coil is shown at 23. It is to be noted that the highest leakage effect, which is obtained when the two primary windings 20 and 21 are in the nearest relative position, principally depends on the total number of the primary turns, whereas the lowest leakage effect, which is obtained when the winding 21 is in its nearest position in relation to the stationary secondary winding, principally depends on the respective numbers of turns of the windings 20 and 21. It is therefore possible, by properly choosing these numbers of turns, to obtain the maximum and minimum desired values of the secondary current and to simultaneously maintain an angular movement of 180° of the movable winding, if this is deemed useful.

This disposition further affords the advantage of reducing the dimensions and the weight of the movable part and involves a better utilisation of the free space in the opening of the magnetic circuit.

The transformers according to the invention can be provided with windings having a number of taps to allow the obtaining of several ranges of control or several values of no load voltage. It is also possible to associate these transformers with other appliances such as reactance coils, capacities, resistances, or choke coils for three phase-single phase systems, current rectifiers, etc. One can also use simultaneously several of these transformers to constitute polyphase systems, for example the three phase-two phase system for electric arc welding.

It is advantageous, for certain applications of these leakage transformers, to use a support of the movable winding so constructed that under the influence of the electromagnetic repulsion, the movable winding assumes an elastic displacement in relation to its equilibrium position of no load conditions, which permits the use, during a very brief space of time when the output circuit is put under load, of a current higher than the current necessary when under load. For this purpose, the mechanical device that connects the winding to the driving axle can either be flexible in the direction of the angular displacements and assume elastic deformations of position, or can be provided with a system of articulations and springs, the latter being adjustable if necessary. When the utilisation circuit is put under load, the current intensity attains a predetermined value which corresponds to the equilibrium position of no load conditions, then it progressively decreases until the winding assumes a new equilibrium position, under the simultaneous influences of its inertia, of the electromagnetic repulsion, of the elastic tension exerted on the support and eventually of gravity.

Figure 4 shows diagrammatically a device which allows the movable winding to assume elastic displacements in relation to its equilibrium position of no load conditions. The support of the winding 24 movable along the magnetic circuit 25 is provided with a piece 26, that rotates about the axle 27 under the action of the driving means of this support, and with a piece 28 to which is fastened the movable winding and which is articulated at 29 on the piece 26. This piece 28 can rotate between two stops 30 and 31. A spring 32 biases the piece 28 against the stop 30; the tension of this spring is adjustable by displacing in a slot 33 of the piece 26 the block to which is attached an end of this spring. A weight 34 is fixed to the piece 28 for increasing the inertia of the whole device which rotates about the axle 29. When the utilisation circuit is put under load, the electromagnetic repulsion exerted on the coil 24 has the effect of causing it to rotate about this articulation in the direction indicated by the arrow. The internal dimensions of the winding makes this displacement possible.

Transformers in which current circuits are provided for several purposes which involve different electric characteristics can also be constructed according to the invention. One and same transformer can for instance be constructed for electric arc welding and for resistance welding. One can, in this case, use windings with several taps, the sections of which, in their different parts, correspond to the required current intensities. One can also use several primary and secondary windings, the movable parts of these windings being then preferably attached to the same support.

In the Figure 5, relating to a transformer for electric arc welding and resistance welding purposes, the apparatus is provided with a single primary winding constituted by the stationary coil 35 and the movable coil 36, which are connected in series. The secondary winding used for electric arc welding is illustrated in 31: it is wound on the core opposite the core on which the stationary primary winding is wound. A second secondary winding 38, independent of the first one, is wound concentrically with the winding 35. The number of its turns and their section correspond to the voltages and current intensities involved in resistance welding.

It is to be noted that this transformer func-

tions for electric arc welding in an identical manner to the transformer illustrated in Figure 3. The minimum coupling corresponds to the position in which the two coils of the primary winding are nearest one to the other. On the other hand, in resistance welding, the maximum coupling and therefore the highest current intensity is obtained in the position where the two primary coils are nearest one to the other.

5 10 What I claim is:

1. In a closed magnetic circuit transformer, an incurvated core, two straight core legs in alignment with the end parts of the incurvated core, a yoke bridging the ends of said core legs, a primary winding movable along said incurvated part, a first stationary winding mounted around one of the straight core legs and providing the secondary of an external utilisation circuit and a second stationary winding electrically independent from the first stationary winding, mounted around the second of the straight core legs and providing the secondary of a second external utilisation circuit.

15 20 25 2. A transformer of the character described, comprising a closed-magnetic-circuit core having

a semi-circular portion, straight core extensions projecting contiguous with the opposite ends of said semi-circular portion, a yoke bridging the free ends of said core extensions, a stationary coil mounted upon one of said core extensions and a movable coil displaceable arcuately on said semi-circular portion about an axis corresponding substantially to the radial center of said semi-circular portion.

3. In a variable leakage transformer having a magnetic circuit formed from laminated material, a plurality of stationary coils and a movable coil, the magnetic circuit comprising a core embodying a straight yoke, a short core section at each end of said yoke and extending at right angles thereto, one of said stationary coils being mounted on each of said core sections, a semi-circular core portion bridging the free ends of said short core sections to close the magnetic circuit, said movable coil being disposed around said semi-circular core portion and movable through a full 180° arc, whereby said movable coil can be closely coupled to either of said stationary coils.
